Primary Examiner — Cynthia R Underwood(74) *Attorney, Agent, or Firm* — Lowe Graham Jones PLLC(57) **CLAIM**

I claim the ornamental design for a turntable with bins, as shown and described.

DESCRIPTION

FIG. 1 is a top perspective view of a turntable with bins, showing my new design.

FIG. 2 is a front elevational view of the turntable with bins.

FIG. 3 is a rear elevational view of the turntable with bins.

FIG. 4 is a left side elevational view of the turntable with bins.

FIG. 5 is a right side elevational view of the turntable with bins.

FIG. 6 is a top plan view of the turntable with bins; and, FIG. 7 is a bottom plan view of the turntable with bins. Features shown in broken lines form no part of the claimed design.
